UNITED STATES PATENT OFFICE.

ERWIN HARRIS OAKMAN, OF ATLANTA, GEORGIA.

ATTACHMENT FOR AUTOS.

Application filed November 17, 1925. Serial No. 69,639.

This invention aims to provide a simple means whereby a driver of a vehicle can impart, to pedestrians and to the drivers of other vehicles, information as to the direction in which the vehicle is to be operated.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in side elevation, a portion of an automobile whereunto the device forming the subject matter of this application has been applied; Figure 2 is a sectional view of the operating mechanism; Figure 3 is a longitudinal section of the coupling and attendant parts; Figure 4 is a section of the indicator; Figure 5 is an elevation showing the switch; Figure 6 is an elevation showing the latch mechanism; Figure 7 is an elevation showing the bracket; Figure 8 is an elevation showing the indicator; Figure 9 is an elevation disclosing a modification.

The numeral 1 marks an automobile comprising a radiator 2 and a front wall 3, adjoining the cowl 4. An upstanding bearing bracket 5 is carried by the radiator 2. A tubular guard 6 is mounted in the upper end of the bracket 5 and on the top of the cowl 4 by a rectangular tubular extension 36 and extends through the front wall 3. A fixed switch member 7 is threaded on the rear end of the tubular guard 6. The switch member 7 is held in place by a securing element 8 in the hub of the switch member and engaging the guard 6. A coupling 9 is threaded on the forward end of the guard 6 and is held in place by a securing element 10. The coupling 9 has an intermediate transverse partition 11.

The numeral 12 marks a cup-shaped keeper having seats 14 in its edge. The hub of the keeper 12 is threaded on the rear end of the guard 6 and a securing element 15

in the hub of the keeper holds the keeper on the guard 6. A shaft 16 is journaled for rotation in the partition 11 of the coupling 9 and in the hub of the keeper 12. A yoke 17 is secured to the rear end of the shaft 16. A handle 18 is pivoted at 19 to the yoke 17. The handle 18 may be swung on the pivot element 19 to engage the handle in the seats 14 of the keeper 12.

The numeral 20 marks an indicator including a head 21 and a tail 22. In the body portion of the indicator 20 there is a longitudinal tube 23. The tube 23 has a rectangularly disposed extension 24. The rear end of the extension 24 is received for free rotation in the forward end of the coupling 9. A cup-shaped connector 25 is mounted in the rear end of the part 24. The connector 25 has a reduced neck 26. The neck 26 is threaded on the forward end of the shaft 16 and is held thereon by a securing device 27. A securing member 28 unites the connector 25 with the rear end of the part 24. In the tube 23 of the indicator 20 there is a weight 29 which holds the indicator in a vertical position, with the tail 22 of the indicator uppermost. Electric lamps 30 are mounted in the ends of the part 23 of the indicator 20. The conductors 31 for the lamps 30 extend backwardly through the part 24 of the indicator, through the partition 11 of the coupling 9 and through the guard 6 and the rectangular tube extension 36, the conductors 31 being joined to terminals 32 on the switch member 7. A movable lever 33, constituting a switch member, is mounted to swing on the tube 6 behind the switch member 7. The lever 33 is adapted to cooperate with the terminals 32 to close the lamp circuit and to open it. The lever 33 is pressed forwardly, so that it will cooperate with the terminals 32, by means of a compression spring 34 disposed about the rear end of the guard 6, one end of the spring abutting against the hub of the keeper 12 and the other end of the spring abutting against the lever 33. The conductors 31 are wound loosely, as at 35, around the neck 26 of the connector 25, thus putting enough slack into the conductors so as to permit the shaft 16 to be rotated.

When the handle 18 is disengaged from the seats 14 of the keeper 12, the weight 29 causes the indicator 20 to stand vertically, with the tail 22 of the indicator uppermost.

The operator can rotate the shaft 16 by means of the handle 18, and engage the pivotally mounted handle 18 in one of the seats 14 of the keeper 12. Then the head 6 21 of the indicator 20 will point to the right or to the left, thereby giving the necessary signal and return to vertical position automatically when the handle is released. The operator can open and close the lamp circuit 10 by swinging the switch member 33 with respect to the terminals 32.

If desired, as shown in Figure 9, the indicator 20^a may be so weighted that the head of the indicator, rather than the tail of the indicator, will be uppermost. In Figure 9 15 wherein the modification above mentioned is shown, parts hereinbefore described have been designated by numerals previously used, with the suffix "a".

20 What I claimed is:—

1. In an automobile direction signal: a vehicle including a front wall, a rigid tubular guard mounted horizontally on the vehicle and extending through the wall, a shaft 25 supported for rotation in the guard and a handle on the rear end of the shaft by which it is rotated, a tubular indicator carrying a light, the intermediate portion of the indicator having a rectangular tubular extension connecting with the end of the guard to form a conduit for wires, the extension being secured to the shaft to turn with the shaft and a keeper attached to the rear end of the guard, the handle cooperating with the keeper when desired to hold the indicator in adjusted positions.

2. In an automobile direction signal: a vehicle having a front wall, a rigid tubular guard extending horizontally through the wall, a shaft supported for rotation in the guard, a rightangular handle on the back end of the shaft by which it is rotated and an indicator attached to the front end of the shaft, the indicator being weighted to rotate the shaft and to turn to vertical position, a keeper attached to the back end of the guard, the handle cooperating with the keeper when desired to hold the shaft against rotation.

3. In an automobile direction signal: a vehicle including a front wall, a rigid tubular guard mounted horizontally in front of the wall and extending backwardly through the wall, a shaft journaled for rotation in the guard, an indicator attached to the front end of the shaft to turn with the shaft, the indicator being disposed on opposite sides of the axis of the shaft and being weighted to rotate the shaft and dispose the indicator in vertical position, a handle on the back 60 end of the shaft by which it is rotated, the end of the handle being pivoted to the shaft to permit the handle to move forwardly and backwardly, a keeper attached to the back end of the guard, the forward and backward movement permitting the handle to be en-

gaged in the keeper when it is desired to hold the indicator in adjusted positions.

4. In an automobile direction signal: a vehicle having a front wall, a rigid tubular guard disposed horizontally and extending through the wall, a shaft supported for rotation in the guard, an indicator secured to the front end of the shaft the indicator extending upon opposite sides of the axis of the shaft and being weighted to rotate the shaft and to form a gravity actuated means for disposing the indicator in vertical position, a handle attached to the back end of the shaft by which it is rotated, the handle having its end pivoted to the shaft so that the handle can be moved forwardly and backwardly and assume a position approximately at right angles to the axis of the shaft, a keeper attached to the back end of the guard and having a rim, the rim being provided with notches on each side, the said forward and backward movement of the handle permitting it to be engaged in one of the notches when desired to hold the indicator in adjusted positions.

5. In an automobile direction signal: a tubular guard mounted horizontally on the front portion of an automobile above the hood, a coupling on the forward end of the guard, a shaft supported for rotation in the coupling and means for rotating the shaft, the shaft carrying a tubular indicator having a light, the intermediate portion of the indicator having a rightangular tubular extension, the extension being telescoped into the coupling to form a conduit for wires.

6. In an automobile direction signal: a tubular guard mounted horizontally on the front portion of an automobile above the hood, a shaft supported for rotation in the guard, the shaft carrying an indicator having a light and means for rotating the shaft, the back portion of the guard having a rectangular tubular extension connecting with the top of the cowl, the tubular extension serving the double purpose of a support for the guard and a conduit for wires.

7. In a device of the class described: a vehicle including a wall, a bracket mounted on the vehicle and located in front of the wall, a tubular guard extended through the wall, its front end being supported on the bracket, a coupling mounted on the forward end of the guard, the coupling having an internal partition, a shaft journaled in the partition, means on the rear end of the guard for supporting the shaft for rotation, an indicator provided with a rearwardly prolonged extension of greater diameter than the shaft and a connector secured to the rear end of the extension and having a reduced neck receiving the forward end of the shaft and secured thereto, the neck of the connector being located in the coupling in advance of the partition.

8. A device of the class described constructed as set forth in claim 7 and further characterized by the provision of an electric lamp on the indicator and conductors extending backwardly from the lamp through the extension, through the coupling and through the guard, the conductors being wound loosely about the neck of the connector, thereby to afford the necessary slack for the rotation of the shaft with respect to the coupling.

9. In an automobile direction signal: a tubular guard mounted horizontally on the

front portion of an automobile above the hood, a coupling on the forward end of the guard, a shaft supported for rotation in the coupling and means for rotating the shaft, the shaft carrying a tubular indicator having a light, the intermediate portion of the indicator having a rightangular tubular extension, the extension being telescoped into the coupling to form a conduit for wires.

In testimony that I claim the foregoing as my own, I have hereto affixed my signature.

ERWIN HARRIS OAKMAN.
